UNITED STATES PATENT OFFICE.

CHARLES SPIRO, OF NEW YORK, N. Y.

TYPE-WRITING MACHINE.

SPECIFICATION forming part of Letters Patent No. 400,265, dated March 26, 1889.

Application filed June 4, 1887. Serial No. 240,304. (No model.)

To all whom it may concern:

Be it known that I, CHARLES SPIRO, a citizen of the United States, residing at New York, in the county of New York and State of New York, have invented certain new and useful Improvements in Type-Writers, of which the following is a specification, reference being had therein to the accompanying drawings.

This invention has relation to type-writers, and more particularly to that class which employ type-bars, each carrying a single printing-character and each connected with a key-lever; and the objects of the present invention are to provide a lock for each bar to operate as it approaches and reaches the printing-point, so as to prevent inaccuracy, in the work performed, which would be occasioned by a displacement of the bar laterally, by reason of either resiliency in the bar itself or looseness of the same at its bearings, to provide an improved manner and means for securing the type upon the bars, and for rotating the inking-disk.

Other objects and advantages of the invention will appear in the following description, and the novel features thereof will be particularly pointed out in the claims.

This invention is an improvement upon that set forth in my pending application, Serial No. 234,905; and certain features of construction are herein shown, but not claimed, as they form the subject-matter of said application.

Referring to the drawings, Figure 1 is a substantially central vertical section of a type-bar-carrying plate, the platen, and the inking mechanism, the key-lever connecting-rods being shown in dotted lines. Fig. 2 is a plan of the principal elements shown in Fig. 1. Fig. 3 is a plan of portions of three adjacent type-bars. Fig. 4 is a detail in side elevation of the inking-mechanism, the disk being shown in section. Fig. 5 is a side elevation of a portion of the type-bar and details of the type-securing devices. Fig. 6 is a section, and Fig. 7 a plan, of a modified locking-plate. Fig. 8 shows the locking-grooves, so proportioned as to embrace a different form of type-bar from that shown in Fig. 1.

Similar letters of reference indicate like parts in all the figures of the drawings.

A represents the type-bar-supporting plate, which is provided with a series of concentric grooves, A', in which the type-bar-supporting brackets B are secured.

C represents a shield, which is secured to the front edge of the plate A.

D is the platen mounted on a carriage, D', which rides in a track, D'', secured to the base or table of the machine. A bracket, A'', is mounted on the base and supports the plate A. A bracket, E, projects upwardly from the base and supports a shaft, E', on which a stud, E'', is mounted, and upon the stud, by means of a thumb-screw, E''', the inking-disk F is mounted so as to rotate thereon. A standard, G, projects from the bracket E and carries a gravity-pawl, G', which at its free end remains in contact with the inking-disk.

As described in the application above referred to, the type in the act of moving to the platen comes in contact with the flange F' of the inking-disk and causes it to swing backward and down, as illustrated in dotted lines, Fig. 4, out of the path of the type, whereby the type is inked. In this movement of the disk the gravity-pawl G' is swung outwardly, as shown by dotted lines, Fig. 4, and therefore its free end is caused to travel a short distance in a circular path on the disk. As the type leaves the platen, the disk assumes its normal position, (shown in full lines,) and the pawl following the disk by gravity causes it to rotate a short distance, thus presenting a new surface for inking the next type. This disk-rotating mechanism is exceedingly simple, and has been demonstrated to be completely successful in its operation.

H represents the type-bar, which is mounted in the bracket B by lateral pivots H', and is connected at H'' with a type-lever rod, H''. (Shown in dotted lines.) Each of the type-bars is struck out of comparatively thin light sheet metal, and is provided with a depending lug, H'', near the end of the bar where the type I is located. The lug H''' is formed upon each of the type-bars for the purpose of co-acting with another part to be described, for the purpose of locking the bar at the time the impression is made.

J is a bracket supporting a locking-plate, 100

K, the bracket being fixed to the base of the machine. The locking-plate K is provided with two concentric ribs, K' K². These ribs are concentric with the printing-point, as are the grooves A' of the plate A. Each of the ribs is provided with a series of slots, K³, which are of a width to easily receive a single type-bar. The slots of one rib are placed, preferably, intermediate those of an adjacent rib. I may use one or more locking-ribs.

It will be seen that the locking-plate and its ribs are arranged very near the printing-point, and this is essential to a perfection in the operation, as were the locking-plate arranged farther from the printing-point and nearer to the pivot of the type-bar lateral springing or deflection of the type-bar and any looseness at the pivots thereof would effect a material displacement of the type with reference to the exact printing-point on the platen, because a slight deviation at the pivot, or at the locking-plate near the pivot, would cause an increased and very material deviation at the printing-point. By locating my locking-plate near the printing-point I obtain a very perfect control and alignment of the type-bar.

I adapt my locking device and the type-bars operating in connection therewith to each other in such a manner that each slot of each rib of the locking-plate is capable of locking and aligning a plurality of type-bars. In this instance I illustrate a construction by which each slot aligns and locks three bars.

In Fig. 3, at the left, the type-bar is straight. At the right the type-bar is bent, as at H⁵, while the central bar, H, is bent to a less degree, as at H⁶, so that all three of these adjacently-arranged type-bars are adapted to be brought into a single slot of a locking-rib, and yet the type of each bar will be brought exactly to the printing-point. By this construction and arrangement of these coacting parts it will be seen that I not only reduce the number of locking-slots necessary, but am enabled to arrange the same nearer to the printing-point, and yet permit of a sufficient clearance of each of the type-bars of a series co-operating with the locking-slot, in order that they may pass each other without collision as they are successively brought to and returned from the printing-point, and also as they rest in a position of non-use.

Now it is apparent that so far as the locking feature of this invention is concerned the locking-plate or its separate locking-ribs may be sufficiently elevated to co-operate with type-bars which are not provided with the depending lugs H⁴, as shown in Fig. 8; but I prefer to form the bar as herein shown.

L represents the type-receiving block, which is slotted, as at L', for the reception of the type-bar. It is centrally bored, as at L², for the reception of a roughened shank, I', of the type or type-plug I, the type N being either formed on or secured to the face M of

the plug I. The fit of the shank I' is comparatively loose or easy within the plug L, and the type-bar being straight, there will be at each side thereof an aperture or a portion of the bore L², into which melted solder may be poured, so that it shall flow down the sides of the bar and around the shank of the type-plug. This pouring of the solder takes place after the type-plug has been inserted into the block and the block adjusted longitudinally on the bar, so as to bring the type to the printing-point, and after the type-plug has been turned within the block for the proper adjustment of the type to cause it to print in a correct vertical line. After the type-plug and block are adjusted and fixed by solder such portions of the plug, and, if desired, similar portions of the block which are outside of the area of the printing-character proper, may be removed, whereby greater clearance of the type-bars, one from the other, is provided. The dotted lines X in one of the details of Fig. 5 indicate the portions removed for this purpose. In this manner the parts specified are properly adjusted and permanently secured in a cheap, rapid, and efficacious manner.

By beveling the portions of the locking-ribs between the slots thereof it will be seen that any slight variation of a type-bar from a true alignment is overcome, and the same is brought into proper alignment by being guided into the slot by said bevels of the ribs. In this manner quite material imperfections in the pivoting of the bar are overcome and good work accomplished.

In Figs. 6 and 7 I have illustrated a more easily constructed locking-plate, in that the slotted ribs K' K² are replaced by rows of pegs K' K². These pegs are slightly tapered and are driven in holes formed in the plate K, and they are arranged so as to form slots or spaces between each two pegs, into which spaces the type-bars H or lugs H⁴ thereon pass, so as to lock the bars against lateral displacement from the printing-point.

Having described my invention and its operation, what I claim is—

1. In combination with the type-bars of a type-writing machine, a locking-rib having slots, the slots and type-bars being relatively constructed so that two or more bars are locked by one and the same slot in the rib, substantially as specified.

2. In a type-writing machine, a series of type-bars pivoted in brackets mounted in a series of grooves concentric with the printing-point, in combination with a locking-plate having a rib concentric with the printing-point, and provided with slots for the reception of the type-bars, substantially as specified.

3. The combination of a type-bar, a block slotted to embrace the same and longitudinally bored for the reception of a type-bearing plug, the bore of the block extending from end to end thereof and forming pas-

sages at each side of the bar, substantially as specified.

4. A type-plug having a roughened shank, in combination with a block bored longitudinally to receive the same loosely, and slotted to a width less than that of the bore, and with a type-bar, substantially as specified.

In testimony whereof I affix my signature in presence of two witnesses.

CHARLES SPIRO.
